CLAIM

The ornamental design for a ball-hitch for bicycle carrier, as shown and described.

DESCRIPTION

FIG. 1 is a perspective view of a ball-hitch for bicycle carrier showing my new design, it being understood that the broken lines are for illustrative purposes only and form no part of the claimed design;

FIG. 2 is an enlarged front elevation view thereof;

FIG. 3 is an enlarged top plan view thereof;

FIG. 4 is an enlarged side sectional view thereof taken along line 4—4 in FIG. 2;

FIG. 5 is an enlarged side elevation view thereof, the opposite side being a mirror image of that shown;

FIG. 6 is an enlarged bottom plan view thereof; and, FIG. 7 is an enlarged rear elevation view thereof.

*FIG. 4**FIG. 5**FIG. 6**FIG. 7*
